UNITED STATES PATENT OFFICE

MANTON E. JOHNSON, OF ST. LOUIS, MISSOURI

SIGNALING DEVICE

Application filed February 11, 1928. Serial No. 253,752.

This invention relates to a signal device for motor vehicles and the like, the general object of the invention being to provide means for indicating when the vehicle is to be turned to the right or left or is to be stopped, the device being intended to be so arranged in the vehicle that it will project from the top thereof so that the signal means can be seen from all directions.

Another object of the invention is to make the right and left hand signal means in the form of an arrow with an electric lamp for illuminating the arrow, the current being automatically turned on when the arrow is moved to operative position, with means for closing the circuit of the lamp by hand when a stop signal is to be given.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:-

Figure 1 is a top plan view of the device.

Figure 2 is an elevation, showing portion of the vehicle in dotted lines.

Figure 3 is a section on line 3-3 of Figure 1.

Figure 4 is a section on line 4-4 of Figure 3.

Figure 5 is a section on line 5-5 of Figure 3.

In these views, the numeral 1 indicates an upright cylindrical casing which is formed with a bracket 2 adapted to be fastened to a front part of the vehicle at the top thereof, with the casing extending through a hole in the top of the vehicle, as shown in Figure 2. A hollow spindle 3 passes through the casing and has a cap 4 on its upper part which fits over the upper end of the casing and a lamp casing 5 is connected with said cap, the casing 5 being horizontally arranged with a lens 6 in one

end thereof and said casing has a vertically arranged neck 7 which is suitably fastened to an upright flange 8 on the cap. The spindle 3 extends above the cap into the lamp casing and has a socket for a lamp bulb 9. An arrow 10 is fastened to the lens carrying end of the casing in such a manner that the rays of light from the lamp will illuminate the arrow.

A disk 11 is connected with the lower end of the spindle 3 and closes the lower end of the casing 1, said disk having a rotary fit in the casing. A stem 12 is threaded in the disk and a handle 13 is fastened to the lower end of the stem so that by turning the handle, the spindle 3, with the cap and lamp casing and the parts attached thereto, will be turned in relation to the casing 1. A switch casing 14 is attached to the lower end of the casing 1 and a button 15 is carried by said casing, the button being normally held projected by the coil spring 16 within the casing 14. The body of the button is provided with a socket in which is arranged a coil spring 17 which acts to hold the head of a headed stud 18 against the bottom plate 19 of the button, the stem of the stud passing through a hole in said bottom plate.

A ring 20 having a recess 21 therein is fastened to a ring 22 carried by the spindle 3, the ring 20 being insulated from the ring 22 by the insulation 23. A conductor 24 connects the ring 20 with one of the terminals of the lamp socket and a conductor 25 is connected with the stud 18 and is also connected to the battery of the vehicle or other source of supply so that when the stud contacts with the ring 20, the circuit to the lamp will be closed. The disk 22 is provided with a number of small recesses 26 in its periphery, any one of which is adapted to be engaged by a ball 27 arranged in a tubular member 28 connected with the bracket 2, a coil spring 29 in the member 28 tending to force the ball outwardly. This arrangement acts as a lock for holding the spindle 3 and the parts associated therewith in adjusted position.

When the parts are in a neutral position, the ball will engage the middle recess 26 of

the valve 22 and thus hold the parts with the arrow pointing rearwardly. In this position of the parts, the recess 21 in the ring 20 will be opposite the stud 18 so that said stud is 5 out of contact with the ring and the circuit to the lamp will be broken. If the driver wishes to signal that he is to stop or slow up, he would push the button 15 inwardly and thus cause the stud 18 to engage the recessed part 10 of the ring 20 and thus close the circuit to the lamp, which would indicate that the car is to be stopped or checked. When either a right or left hand turn is to be made, the operator pushes upon the handle 13 in the proper 15 direction to move the spindle 3 a quarter turn so that the arrow will point in the direction the vehicle is to turn. The detent 27 will hold the parts in adjusted position. As the spindle is turned, the disk 20 turns with 20 it so as to cause a part of the disk to contact the stud 18 and thus close the circuit to the lamp to illuminate the arrow in its operative position. After the turn has been made, the operator moves the device to its neutral position, which will bring the recessed part of 25 the disk opposite the stud and thus break the circuit to the lamp.

It is thought from the foregoing description that the advantages and novel features 30 of my invention will be readily apparent.

It is to be understood that I may make changes in the construction and in the combination and arrangement of the several parts, provided that such changes fall within 35 the scope of the appended claim.

What I claim is:—

A signal of the class described comprising a signal including a casing, a lamp in the casing, means on the casing and cooperating 40 with said lamp for giving a direction indication, a stem on said casing, a support means mounting said stem for rotation on said support, the latter including a casing surrounding said stem, an annular contact member 45 having a peripheral recess on said stem within said casing, means electrically connecting said contact to one side of said lamp, means for rotating said signal casing and stem to either side of a central neutral position, a 50 push button, means mounting a resilient contact on said push button, said push button including an insulating member, means mounting said member on said casing for movement toward and from said annular contact member, spring means for normally holding said member and contact spaced from the annular contact whereby a circuit 55 may be closed to the lamp by manually pressing the push button when the signal element is in the central position, said circuit being automatically closed when the signal element is moved to the right or left of its central position.

In testimony whereof I affix my signature.

MANTON E. JOHNSON.
